UNITED STATES PATENT OFFICE.

EDWARD T. COLLINGS, OF PHOENIX, ARIZONA.

HARROW-TOOTH.

1,116,997.

Specification of Letters Patent.

Patented Nov. 10, 1914.

Application filed July 21, 1914. Serial No. 852,301.

To all whom it may concern:

Be it known that I, EDWARD T. COLLINGS, citizen of the United States, residing at Phoenix, in the county of Maricopa and 5 State of Arizona, have invented certain new and useful Improvements in Harrow-Teeth; and I do hereby declare the following to be a full, clear, and exact description of the invention, such as will enable others skilled 10 in the art to which it appertains to make and use the same.

This invention relates to harrow teeth, and more especially to those which are resilient so that they may spring when in use; 15 and the object of the same is to provide an improved reinforcement for such a harrow tooth.

The present invention is designed primarily as an improvement on the construction 20 disclosed by Letters Patent issued to me No. 1077806, on November 4, 1913. While the harrow tooth in that case gives excellent service under most conditions and in most soils, I find that extremely hard ground 25 causes the tooth to either break or straighten out, and it is the purpose of the present invention to provide a reinforcement which will strengthen the harrow tooth at the point where it needs strengthening when 30 used on extremely hard ground. This reinforcement is in the shape of a leaf, somewhat like those employed in vehicle springs, but it is of especial form adapting it to be secured at one end to the body of the 35 harrow tooth and to follow the curvature thereof. Details will be found in the following specification, and are illustrated in the drawings wherein—

Figure 1 is a side elevation of my improved harrow tooth with its reinforcement applied, Fig. 2 is a bottom plan view of Fig. 1. Fig. 3 is a cross section on the line 3—3 of Fig. 2, and Fig. 4 is a side elevation of the reinforcement alone.

45 In the drawing hereto attached I have used reference letters to refer to the harrow tooth forming the subject matter of my prior patent, and reference numerals to refer to the reinforcement which forms the 50 subject matter of the present application. With that understanding, the letter B designates the body of the harrow tooth which is secured to the tooth bar at the point S and which has its lower end or point P extending forward and standing beneath the point 55 of attachment to the tooth bar, said lower

end or point being channeled on the under side as at C in Fig. 2 and rounded at its front end or tip T as explained in my former patent, wherein the channeling of the point 60 and the rounding of the tip produce effects which are extremely advantageous.

Coming now to the details of the present invention, the reinforcement forming the subject matter thereof is a strip of steel of 65 substantially the same width as the body of the harrow tooth, and its shape in side elevation is best seen in Fig. 4. Its body 1 follows the curvature of the body of the tooth and stands behind and in close contact with said body, its upper end is bent 70 at right angles into a shoulder 2 adapted to rest against one edge of a clip plate 3 which overlies this end of the reinforce as seen in Fig. 1, and all parts are clamped together 75 by means of a U-shaped bolt or clevis 4, thus rendering them detachable and adjustable. The lower end of the reinforce is channeled as best seen at 5 in Fig. 2, its extremity or tip is rounded or contracted as best seen at 80 6 in the same view, and the channeled portion runs out at about 7 in Fig. 1 where the channeled portion of the tooth T runs out.

From the above description it will be seen that the reinforce is applied to the body B 85 of the tooth midway between its upper end which is attached to the support and the lower end or point P, and therefore the reinforce does not interfere with the attachment or spring of the upper end of the tooth 90 nor with the action of the lower end thereof on the ground. As first above stated, the purpose of the reinforce is to strengthen the tooth where the latter ordinarily breaks if the ground is extra hard, but the use of 95 the clevis 4 and plate 3 permits of the adjustment of the reinforce or its removal if necessary. By channeling the lower end of the reinforce as at 5 and extending it into the channel C of the tooth, the latter is permitted to have its ordinary movements and the reinforce slides in the channel thereof, and moreover the inter-engagement of the channeled parts of the two members prevents the lower end of the reinforce from 105 slipping laterally off the tooth, while the upper end is of course held in place by the connection described.

I do not wish to be limited to the material, proportion, or size of parts, and 110 changes in or additions to the details may be made at will.

What is claimed as new is:—

1. The combination with a spring harrow tooth secured at its upper end to a support and having a channeled point at its lower end; of a spring reinforce standing midway between the ends of the tooth and in rear of and conforming with the curvature of its body, and means for detachably and adjustably securing the upper end of the reinforce to the body of the tooth.
- 10 2. The combination with a spring harrow tooth secured at its upper end to a support and having a channeled point at its lower end; of a spring reinforce standing midway between the ends of the tooth and in rear of and conforming with the curvature of its body, the upper end of the reinforce being bent at right angles away from the tooth into a shoulder, a clip plate lying 15 against the rear face of the reinforce and at one edge against said shoulder, and a clevis connecting the plate with the tooth and clamping the reinforce between them.
- 20 3. The combination with a harrow tooth secured at its upper end to a support and having its lower end channeled on its under side, its body between said ends being bent;

of a spring reinforce conforming with the curvature of said bent body and lying against the rear side of the same, its lower end being channeled and extending for a distance along the channel at the lower end of the tooth, and means for securing its upper end to said body.

30 4. The combination with a harrow tooth secured at its upper end to a support and having its lower end channeled on its under side, its body between said ends being bent; of a spring reinforce conforming with the curvature of said bent body and lying against the rear side of the same, its lower end being channeled and extending for a distance along the channel at the lower end of the tooth; a clip plate lying against the rear face of the reinforce at its upper end, and a clevis whose bend engages the reinforce and tooth and whose extremities are detachably connected with said plate.

35 In testimony whereof I affix my signature in presence of two witnesses.

EDWARD T. COLLINGS.
